UNITED STATES PATENT OFFICE

WILLIAM H. BOSWORTH, OF YONKERS, NEW YORK, ASSIGNOR TO GEORGE HAISS MANUFACTURING CO. INC., OF NEW YORK, N. Y., A CORPORATION OF NEW YORK

WAGON LOADER

Application filed October 24, 1929. Serial No. 402,167.

This invention relates to wagon loaders and excavators, and is directed particularly to the digging and feeding mechanism of such machines.

5 The primary object of this invention is to provide a novel digging and feeding mechanism by which the operation of such a machine as that to which the present invention relates may be satisfactorily carried out under adverse conditions, as when, for example, the material to be handled is of such a nature as to require loosening or breaking up thereof before it can be effectively acted upon by the material-propelling means.

10 To the above end the present invention contemplates the use of a plurality of digging elements or picks for loosening or breaking up firmly packed and frozen material, such as soil, earth, sand, gravel and the like, in combination with rotatable material-propelling means comprising screw-like members, and more specifically suitably supporting screw-like ribbons for moving the loosened or broken-up material into the path of the conveyor by which such material is picked up, elevated and discharged into a truck or other vehicle adapted to receive the same, the digging elements or picks being in contact with the respective inner faces of the screw-like ribbons and carried by a plurality of rotatably disposed arms which also serve to support the ribbons with respect to the driving shaft of the material-propelling means.

15 Other objects and advantages of the invention will become apparent from the following description, taken in connection with the accompanying drawings in which—

Figure 1 is a side elevation of the pick-up end of a wagon loader and excavator embodying this invention; Figure 2 is an end view of the machine as viewed from the right in Figure 1; Figure 3 is an enlarged detail sectional view taken on line 3—3 of Figure 2, and showing the relation of the digging elements or picks to their associated screw-like ribbon; Figure 4 is a perspective view of one of the arms for supporting the screw-like ribbon at the left in Figure 2; and Figure 5 is a sectional view taken on line 5—5 of

Loaders of the type above mentioned, include a frame 9 adjustably mounted upon a traction device 10 by which the machine may be propelled from place to place and crowded at slow speed toward and into the material to be excavated, there being a power unit such as an internal combustion engine (not shown) employed as a driving means for the traction device as well as for the bucket conveyor 11. This conveyor includes a plurality of buckets 12, carried by a pair of chains 13, passing over sprockets, of which the lower sprockets 14 only are shown, these sprockets being secured to the intermediate position of a shaft 15, which is journaled at 16 in the lower end of the frame 9 and extends transversely of the machine. It will be understood that the driving connection between the power unit and the conveyor chains 13, which drive the shaft 15, is such that this shaft is rotated in the direction of the arrow A in Figure 1.

Secured to the portions of the shaft 15, which extend from each side of the journal boxes 16, are a plurality of radially projecting and laterally disposed arms 19. These arms are provided at their outer ends with bevel faces 20, the faces of the arms at one side of the shaft being oppositely disposed to the faces of the arms at the opposite side of the shaft so as to accommodate a pair of oppositely pitched or inclined screw-like ribbons 22, the pitch of the ribbons being such that their respective inner surfaces constitute their working faces as the shaft 15 is rotated in the direction of the arrow A in Figure 1. Preferably these screw-like ribbons are secured to the ends of the arms 19 by a plurality of bolts 23, as shown most clearly in Figure 5, and the bolts of each arm serve also to secure thereto a pick or digging element 24. Each of these digging elements is tapered to a relatively sharp entering edge at its forward end, the taper being such that its inner and outer faces 25 and 26 are at an angle of preferably 30-35° to each other. It will be noted that the entering edge of each pick projects slightly, as, for example, 11/2", beyond the peripheral margin of the screw-like ribbon 22 and that the greater portion of the outer face 26

50 Figure 3. 100

lies within the circumference of the screw-like ribbon. By reason of the disposition of the entering edge of the pick, the material to be loaded is subjected to the action of the 5 digging elements beyond the peripheral margin of the screw-like ribbon, thus providing for ease in rotation of the material-feeding mechanism at a considerable saving in power. Moreover, by reason of the fact that the outer 10 face of each digging element is slightly inclined from the entering point of the pick towards the center of rotation of the material-feeding mechanism, the outer faces of these teeth are not required to slide over the tightly 15 packed material at the rear of the entering edges of the teeth as they pass through the material, with the result that a further saving in power is effected. As a result of the inclination of the inner faces 25 of the digging elements, the material being acted upon by them is permitted to pass easily up over such faces as the teeth pass through the material and impart to it a combined skimming and plowing action which, together with the upwardly and 20 forwardly directed impacts delivered by the series of teeth to the material to be loaded, effectively break up such material so that the screw-like ribbons may easily move the material acted upon towards and into the path 25 of the buckets 12 of the conveyor.

Regardless of whether the machine is employed in the handling of loose or compact material, the path of travel of the conveyor buckets is cleared by the buckets themselves, 30 which, due to the provision of digging teeth 27 on the forward edges thereof, can be forced forwardly and through the material with comparative ease. The path which is cleared by the buckets provides room to receive the 35 material which is moved inwardly from opposite sides of the conveyor by the material-propelling means as the machine advances toward and into the material to be loaded or excavated.

40 Although only one form of the invention is herein shown and particularly described, it will be understood that certain modifications may be employed without departing from the spirit of the invention or the scope of the following claim, as, for example, more or less digging elements than are herein shown may be employed, and likewise the provision for more or less radially disposed arms 19 may be made, as desired.

45 What is claimed is:

A machine of the character described comprising a conveyor having buckets adapted to receive material at the pick-up end of the conveyor and elevate it to the discharge 50 end of the same, a rotatable shaft located at the pick-up end of said conveyor and projecting outwardly beyond opposite sides thereof, a plurality of laterally spaced and radially disposed arms carried by said shaft at opposite ends thereof, a plurality of digging ele-

ments secured to the outer ends of said arms and adapted to impart forwardly and upwardly directed impacts to the material, and rotatable screw-like members disposed intermediate said digging elements and their respective arms, said screw-like members being oppositely pitched for moving the material acted upon by the digging elements toward and into the path of the conveyor buckets.

70 In testimony whereof, I have affixed my 75 signature to this specification.

WILLIAM H. BOSWORTH.
